1

Our invention relates to protective relaying systems utilizing distance-responsive relays for protecting transmission lines against faults.

The principal object of our invention is to provide a reorganization of such a protective system in such manner as to make it possible to utilize a sensitive or third-zone distance-element carrying but a single contact.

A more specific object is to so correlate the timers in the plurality of protective relaying equipments for a plurality of line-sections terminating in a common bus, that the third-zone tripping-contacts of different timing relays momentarily close at different times, so that an extremely fast-moving third-zone distance-responsive contact does not need to be connected in this particular tripping-circuit in order to safeguard against a faulty tripping-operation, as will be subsequently described. A more specific object of our invention is to provide a novel timer-control whereby the timer is under control of the directional relay-element as well as the third-zone relay-element.

A further object of our invention is to provide a carrier-current protective relaying system in which the third-zone distance-responsive contacts which are utilized to initiate the carrier-current transmission are each connected in series with the coil of an auxiliary relay, so as to eliminate the necessity for any other contacts whatever on the sensitive third-zone distance-responsive elements. In order to make this carrier-starting control feasible, notwithstanding the additional voltage-drop which is introduced by including the coil of the auxiliary relay in the carrier-starting control-circuit, it is usually necessary, in practicing our invention, to bias the cathode of the transmitter oscillator tube to some intermediate potential between the potentials of the terminals of the source of electrical energy for the oscillator tube.

A still more specific object of our invention is to apply the oscillator-controlling circuits just mentioned to a small auxiliary oscillator which is provided as a part of an electronic keyer. This keyer, without our special single-contact third-zone element, is described and claimed in a companion application of Herbert W. Lensner, Serial No. 530,134, filed April 8, 1944.

Prior to our present invention, a standard distance-type relaying system has utilized a third-zone distance-responsive element having a make-contact, an independent, bridge-type, make-contact, and a back-contact. The back-contact was needed for the purpose of aiding in the selective

2

control of an auxiliary relay which provided additional contacts which were responsive to the third-zone distance-response. The first make-contact was required for performing a quick response or function, either associated with the starting of carrier-current transmission, or, even when there was no carrier, in connection with out-of-step protection and for other purposes. The bridge-type make-contact was needed for providing high-speed coordination for preventing faulty tripping in the third-zone timer tripping circuits, which have already been referred to, and which will be explained more in detail hereinafter.

15 The effect of the previously common, multiple-contact construction of the third-zone distance-element has been not only to complicate the structure and render it difficult to adjust, but it has "loaded up" the moving element of the relay 20 so much that its impedance response-characteristic has been affected. These disadvantages are avoided in our new arrangements, utilizing the simplified, or single-contact, third-zone distance-element.

25 With the foregoing and other objects in view, our invention consists in the systems, circuits, combinations, parts and methods, hereinafter described and claimed, and illustrated in the accompanying drawing, wherein:

30 Figure 1 is a single-line diagram which will be referred to in the explanation of the advantages and operation of our invention, and

35 Fig. 2 is a diagrammatic view of circuits and apparatus embodying our invention in a preferred form of embodiment.

Fig. 1 indicates the application of our invention to the protection of a three-phase transmission-line 3, which is indicated in Fig. 1 in single-line diagram. The transmission-line extends 40 between a plurality of stations M, N, O, P, etc., which are represented by three-phase buses which are indicated, in Fig. 1, as single vertical lines. In general, it may be assumed that each station-bus represents a three-phase system 45 which, in the general case, will include synchronous generators as well as load-devices. The transmission-line 3 is sectionalized at the several stations, by being provided with circuit-breakers 4 to 10 at the several line-terminals which are connected to the several buses M, N, O and P.

In Fig. 1, a three-zone distance-responsive protective system is indicated, in connection with stations N and O, by means of stepped lines 6Z1—6Z2—6Z3 and 8Z1—8Z2—8Z3 which are associated with the breakers 6 and 8, respectively,

to indicate a first zone Z_1 in which the tripping-response is substantially instantaneous, a second zone Z_2 in which the tripping-response is obtained only after a time-delay which is symbolically indicated by a vertical step in the line, and a third zone Z_3 which is associated with a still longer time-delay.

Our invention relates to the terminal relaying equipment such as would be utilized at any one of the line-terminals 4 to 10 in Fig. 1. For purposes of illustration, we have shown in detail, in Fig. 2, the terminal equipment which is associated with the breaker 6 at the station-bus N.

The various relays which make up our protective-relaying system include various line-responsive relays, the various coils and contacts of which are separated into alternating-current circuits and direct-current circuits, respectively, the various circuits being arranged, so far as practicable, after the matter of a schematic diagram or "across-the-line" diagram. In each case, the main or operating coil of the relay is given a letter-designation or legend, and the same letter-designation or legend is applied to all of the contacts of that relay. The relays and switches are invariably shown in their open or deenergized positions. When a given relay has, in addition to its main or operating winding, an auxiliary winding, such as a restraining or polarizing coil or winding, the auxiliary winding is given the same letter-designation, with a subscript. Arrows or dotted lines are used, to symbolically indicate how the various parts of each relay are connected together. When corresponding elements are utilized in different phases, they are distinguished by suffixes, such as A, B and C, for the different phases.

In Fig. 2, the breaker 6 is illustrated as a three-pole breaker, having its several poles associated with several line-conductors of the three-phase line 3. The breaker is illustrated as being provided with an auxiliary make-contact switch 6_a , and a trip-coil TC. The protective relaying equipment for controlling the breaker 6 comprises four relaying panels 11, 12, 13 and 14—one for each phase, and one for ground-fault responses.

The phase-A relay-panel 11, for example, includes a directional element DA which has a current-coil DA, a voltage-coil DA_v , and a make-contact DA, the latter being shown off to one side, in connection with the direct-current relaying-circuits. The phase-A panel 11 also includes first, second, and third-zone distance-responsive relaying-elements having current-responsive operating-coils Z_1A , Z_2A and Z_3A , respectively, and voltage-responsive restraint-windings which are grouped together under the designation ZAv . These distance-relays are each provided with a make-contact which is completely identified by using the relay-designation Z_1A , Z_2A , or Z_3A , as the case may be. The three distance-elements Z_1A , Z_2A and Z_3A respond to line-faults at different distances from the relaying station, while the directional element DA responds when said faults are accompanied by a current-direction into the protected line-section at the relaying terminal.

The phase-B and phase-C panels 12 and 13 are similar to the phase-A panel, except that the change in phase is indicated by the substitution of the letters B and C, respectively, in place of the letter A, in the various relay-designations.

The ground-fault relaying-panel 14 in Fig. 2 comprises a directional element DO, having a

current-responsive coil DO and a voltage-responsive coil DO_v , and a single make-contact DO. This panel also includes a heavy-current overcurrent ground-fault detector IO_2 , and a sensitive or light-current ground-fault detector IO_3 , each having a single make-contact which is designated by the appropriate relay designation IO_2 or IO_3 as the case may be.

The relaying energy for energizing the coils of the various relays is obtained from a bank of line-current transformers 15, a bank of auxiliary current-transformers 16, a bank of potential-transformers 17, and a bank of auxiliary potential-transformers 18, as clearly shown in the drawing, and as is well known in the art, so that a detailed description of the connections is not believed to be necessary.

The direct-current relaying-connections of Fig. 2 are shown in schematic form. Attention will first be directed to the three third-zone distance-responsive contacts Z_3A , Z_3B and Z_3C , which are shown about half way down, in the schematic diagram. These third-zone contacts are the contacts which are needed in order to perform a quick-response function, and in the particular relaying system which is shown in Fig. 2, this function consists in the starting of carrier-current transmission by means of a carrier-current transmitter 21, which is a part of a carrier-current equipment also including a carrier-current receiver 22. The carrier-current equipment is illustrated as being coupled to the third phase-conductor of the line 3, through a coupling transformer 23 and a coupling capacitor 24 in a manner which is or may be well known or conventional.

In accordance with our invention, the three third-zone contacts Z_3A , Z_3B and Z_3C are each connected in a separate circuit, in series with the operating-coil of an associated auxiliary relay, the three auxiliary relays being designated CSA, CSB and CSC, respectively, representing contactor-switches for supplying an additional contact or contacts which avoid the necessity for multiplying the number of contacts which are actually carried by the third-zone distance-elements Z_3A , Z_3B and Z_3C . In Fig. 2, the three circuits just referred to extend from the negative bus (—) through the various third-zone contacts, such as Z_3A , Z_3B and Z_3C , respectively, and thence through the associated coils CSA, CSB and CSC, as the case may be, to a common circuit-connection 25, which is connected to the positive relaying bus (+) through a resistance R_1 .

Attention may now be directed to the trip-circuit connections of the schematic diagram in Fig. 2. Various trip-circuit connections are shown, starting with the phase-A directional contact DA, which is connected between the negative bus (—) and a relaying circuit 26. A tripping circuit continues on, from the conductor 26, through the first-zone contact Z_1A , to a tripping bus 27, from which a trip-circuit is continued, extending through the trip-coil TC and the breaker-switch 6_a to the positive bus (+). A second trip-circuit extends from the conductor 26 through the second-zone contact Z_2A to a conductor 28 and thence through a timer-contact T2A to the tripping-bus 27. A third phase-A tripping circuit extends from the conductor 28 through the contact CSA of the auxiliary third-zone relay, to a conductor 29, from which a trip-circuit is continued, through a timer-contact T3A, to the tripping bus 27.

In accordance with our invention, the con-

ductor 29 of the third-zone tripping circuit is also utilized to energize another auxiliary switch CSA1, having a single make-contact CSA1 which is utilized to energize the phase-A timer T-A. The timer T-A is illustrated as utilizing an alternating-current motor which is energized from a suitable alternating-current circuit, as by means of a saturating current-transformer ST. This timer T-A is provided with the second and third-zone contacts T2A and T3A which are momentarily closed after suitable time-intervals following the initiation of the timer-operation.

The phase-B and phase-C tripping circuits, distinguished by the letter-designations B and C, are similar to the phase-A circuits already described, and no further explanation is believed to be necessary, other than to note that the relaying conductor 28 is common to all three phases, and is also connected to the tripping-bus 27 through a contact 31 of a receiver-relay RR, said receiver-relay having an operating-coil RR and a holding-coil RR_H which will be subsequently described. The common phase-circuit relaying-conductor 28 is also utilized to energize the coil CSP of an auxiliary phase-fault relay or contactor-switch CSP, which is thus energized whenever the directional element and the second-zone distance-element both respond, in any one of the three line-phases A, B or C.

Fig. 2 indicates a single ground-fault tripping-circuit which extends from the negative bus (-), through the directional contact DO and the fault-detector contact IO2, to a relaying conductor 32, and thence, through a contact 33 of the receiver relay RR, to the tripping bus 27. The conductor 32 is also utilized to energize the coil CSG of an auxiliary ground-fault relay or contactor-switch CSG.

We come, now, to the three third-zone contacts Z3A, Z3B and Z3C, which have already been described as being utilized to energize the conductor 25 through the respective coils of the auxiliary relays CSA, CSB and CSC. The conductor 25 is primarily utilized to control the operation of an oscillator-tube OSC. In the broader aspects of our invention, any sort of tube-control may be utilized, but in the more specific aspects of our invention, a particular kind of control is preferred. Furthermore, in the broader aspects of our invention, the oscillator-tube OSC may be any oscillation-generator, but in accordance with the more specific aspects of our invention, it is preferred to utilize this oscillator-tube OSC as a part of a so-called electronic keyer, which is utilized to "key" or control the carrier-current transmitter 24, which is provided with its own oscillator-tube OSC'.

In the particular form of keyer-control which is shown in Fig. 2, the keyer-oscillator OSC has its plate-circuit energized from the positive bus (+) through a series dropping-resistor R2, which is connected to a conductor 34, and thence, through a radio-frequency choke RFC, to the anode-lead 25 of the oscillator OSC. The conductor 34 of this plate-energizing circuit is connected to the previously mentioned control-circuit conductor 25, through the serially connected back-contacts CSP and CSG, the mid-point of which is connected, at 36, to a circuit extending to the negative bus (-), and including the ground-fault detector-contact IO3, and preferably also a resistor R3, which may be utilized for the purpose of avoiding a short-circuiting of the auxiliary-relay coils CSA, CSB or CSC. The ground-fault

contact IO3 is utilized to by-pass the phase-fault contact CSP, in order to provide ground-preference in a well-known manner.

In a manner which is also well known, the two serially connected back-contacts CSP and CSG are shunted by a circuit which includes the receiver-relay operating-coil RR and a serially connected resistance R4, thus providing a second circuit which joins the conductors 25 and 34.

- 10 The oscillator OSC is connected to a tuned circuit which includes two capacitors C1 and C2, and the primary winding of a transformer 39. The intermediate point of the two capacitors C1 and C2 is connected to the cathode-lead 40 of the oscillator tube OSC. The junction-point between the capacitor C1 and the transformer-primary 39 is connected to the grid-circuit 41 of the oscillator OSC, and this grid-circuit is connected to the cathode-circuit 40 through a grid-leak GL. The 15 connection-point between the capacitor C2 and the transformer-primary 39 is connected, at 42, through a blocking-capacitor BC, to the anode-lead 35.

In accordance with our invention, we bias the cathode-lead 40 of the keyer-oscillator OSC by connecting it to an intermediate point 43 in a potentiometer 44 that is connected across the terminals (+) and (-) of the unidirectional-current source which energizes the oscillator. The 20 reason for this bias can best be understood by referring to the operation of the oscillator OSC. Normally, this oscillator is in an oscillating condition, receiving power in a plate-anode circuit which can be traced from the positive bus (+), through the series dropping resistor R2, the conductor 34, the radio-frequency choke RFC, the anode-lead 35, the oscillator tube OSC, the cathode-lead 40, and the potentiometer-connection 43, to the negative bus (-). The effective potential 25 which is applied to the oscillator is the potential existing between the points 34 and 43.

This oscillation is stopped whenever any one of the contacts Z3A, Z3B, Z3C or IO3 is closed, the effect of which will be to bring the potential of the point 34 within from zero to some 10 or 20 volts of the potential of the negative bus (-), depending upon how many of these contacts close, and depending also upon the resistance-drop in the coils CSA, CSB or CSC, or the resistor R3 if said resistor is utilized. The potentiometer-connection 43 raises the potential of the oscillator-cathode to a point which is preferably more positive than is the point 34 upon the closure of any one of the control-contacts Z3A, Z3B, Z3C or IO3. In this manner, we are enabled to utilize the controlling-contacts Z3A, Z3B and Z3C in a control-circuit which includes the coils of the auxiliary relays CSA, CSB and CSC, respectively, without running the hazard of having the oscillator OSC maintain its oscillations at a time when it is desired to cut off said oscillations.

The potentiometer-tap potential at 43 is preferably raised to voltage such as 75 volts, considerably higher than the resistance-drop in the auxiliary-relay coils CSA, CSB and CSC, leaving at least 40 volts of the total source-voltage of 125 volts, for the operation of the oscillator OSC. This removes the hazard of chattering contacts Z3A, Z3B, Z3C or IO3, by permitting them to draw an arc of an appreciable length, while still keeping the keyer-oscillator stopped.

The manner in which the keyer-oscillator OSC is utilized, to control the transmitter-oscillator OSC', aside from the use of the control-circuits containing the coils CSA, CSB and CSC, and aside

from the use of the biasing potentiometer-connection 43, is the same as is described and claimed in the previously mentioned Lensner application.

Thus, the output of the transformer 39, in the retuned circuit of the keyer-oscillator OSC, is rectified by connecting the transformer-secondary 45 to a rectifier-valve RV which is loaded through a resistor R5 so that, whenever the keyer-oscillator OSC is generating oscillations, a negative-drop is produced in the load-resistor R5, thus producing a unidirectional controlling-voltage which is applied to the grid of the transmitter-oscillator OSC' in such a way as to block the oscillation of said transmitter oscillator OSC', thereby preventing the transmission of carrier-current energy. The grid-control circuit just mentioned may be traced from the negative bus (—), through the load-resistor R5, and a radio-frequency impedance RFZ, to the grid-circuit 47 of the oscillator OSC' of the carrier-current transmitter 21. Since the keyer-oscillator OSC is normally oscillating, the grid-blocking potential normally appears across the load-resistor R5, and the oscillation-generation of the transmitter-oscillator OSC' is thus normally blocked, so that no radio-frequency energy is normally being transmitted onto the protected line-section by the carrier-current transmitter 21.

The equipment is completed by means of a receiver-relay holding-coil RR_H which is energized in the plate circuit of the receiver-tube REC of the carrier-current receiver 22.

In operation, when any fault occurs upon the transmission system, within the reach of any one of the three sensitive phase-fault distance-responsive relays Z3A, Z3B or Z3C, or within the balance-point of the sensitive ground-fault relay IC3, the potential of the anode-circuit conductor 34 of the keyer-oscillator OSC is brought to a potential which is substantially as negative as, and preferably, to be on the safe side, more negative than, the potential of the potentiometer-point 43 which is connected to the cathode-lead 40 of said keyer-oscillator. This effectually blocks the operation of the keyer-oscillator, and reduces, substantially to zero, the voltage-drop across the load-resistor R5, thus removing the blocking-potential from the transmitter-oscillator OSC' and causing the latter to immediately begin oscillating.

If the line-fault is accompanied by a line-current flowing in the internal direction, or in the direction into the protected line-section 3 at the relaying terminal, one or more of the directional elements DA, DB, DC or DO will operate, and if the corresponding second-zone element Z2A, Z2B, Z2C or IO2 also picks up, then the auxiliary phase-fault or ground-fault relay CSP or CSG will also pick up, opening its back-contact between the conductors 25 and 34, thereby restoring the potential of the point 34 to a value depending upon the relative impedances of the resistances R2 and R4 and the other constants of the circuit, so that the point 34 is sufficiently positive with respect to the potentiometer-point 43 so that the keyer-oscillator OSC begins to oscillate again, thereby restoring the biasing potential which is developed across the load-resistor R5, and thus again blocking the oscillation of the transmitter oscillator OSC'.

It will thus be observed that we utilize the keyer-oscillator OSC by rectifying its oscillatory-current output, by means of a rectifier valve RV which energizes the load-resistor R5 and produces a unidirectional controlling-voltage there-

in. The ripples of this controlling-voltage can be removed, more or less completely, by suitable means which are symbolically indicated by means of a filter-capacitor FC which is connected across the terminals of the load-resistor R5. If this filtering action is sufficiently complete, the frequency of the oscillations of the keyer-oscillator OSC is immaterial. We prefer, however, to utilize a keyer-oscillator frequency which is higher than the frequency of the carrier-current which is produced by the carrier-current transmitter 21, utilizing a keyer frequency which may be of the order of two or three times the transmitter-frequency. Thus the ripples which appear in the voltage-drop across the load-resistor R5 are of a higher frequency than the carrier-current frequency, so that the ripple in the rectified output of the rectifier-valve RV will not modulate the carrier-current energy which is generated by the carrier-current transmitter 21.

In the operation of the tripping circuits as shown in Fig. 2, our present invention is particularly concerned with the operation of the third-zone phase-fault tripping-circuits which include the timer-contacts T3A, T3B and T3C, respectively. Previous to our present invention, it had been customary to initiate the operation of the several timers T—A, T—B and T—C in response to the corresponding third-zone distance-element Z3A, Z3B or Z3C, or through auxiliary relays similar to our relays CSA, CSB and CSC, but differently controlled so that the auxiliary-relay coils were not in series with the distance-element contacts, in the carrier-starting circuits or other circuits requiring a quick response to an operation of any one of the three phase-fault third-zone elements Z3A, Z3B and Z3C. In the previous third-zone tripping circuits, it was also customary to utilize timing-relays having the same time-settings, in the line-terminals which are connected to the station-bus, such as in the line-terminals 5 and 6 of Fig. 1, and it was also customary, and necessary to utilize quick-acting contacts which were actually carried by the third-zone distance-elements, rather than tolerating the slight time-hesitation inherent in utilizing the contacts of auxiliary relays, however fast, such as our auxiliary relays CSA, CSB and CSC.

The reason for this prior-art practice will best be understood by reference to Fig. 1, wherein the relay-operation at the points 5 and 6 at the station N will be considered, for the case of a fault at the location X near the far end of the line-section O—P, assuming load-current normally flowing from the station N to the station M, as indicated by the arrow. With a fault located at the point X, as shown, the fault should normally be cleared by the breaker at 8, but if, for any reason, the fault is not cleared by the breaker 8, the duty will revolve upon the relays at the point N to clear the fault through the third-zone tripping circuit. Reference to Fig. 2 will show that the tripping circuit includes (assuming a phase-A fault) the directional contact DA, the auxiliary third-zone contact CSA, and the timer-contact T3A. Previous to our invention, a Z3A contact was utilized in place of the CSA contact.

By reason of the presence of the directional contacts DA, it follows that the breaker 8 of Fig. 1 will operate under these conditions, but the breaker 5 will not, because while the distance-elements associated with the breaker 5 will reach out to substantially the same distances as those

of the breaker 6, the fault-current direction for the breaker 5 will be in the wrong direction to energize the directional elements which are associated with that breaker. However, immediately upon the clearing of the fault by the third-zone timer-action of the breaker 6, the current-direction in the breaker 5 will immediately reverse, because a load-condition is assumed in which the load-current is flowing from N to M, as shown by the arrow, and hence if, at that moment, the Z3A contact and the T3A contact of the breaker-5 relays were closed, a faulty tripping-operation would be obtained at the breaker 5. It was for this reason that a fast-acting contact, actually carried by the third-zone element itself, was required in the tripping circuit, in the place where we utilize our CSA contact, so that this contact would open faster than the directional contact DA could close, at the moment of clearing the fault at the breaker 6, so that a faulty operation of the breaker 5 would not be obtained.

In accordance with our present invention, we avoid the necessity for very quickly reopening the Z3A contact which was previously utilized in the third-zone tripping-circuit, by making the timers of the relaying equipments associated with the breakers 5 and 6, in the illustrated case, momentarily close their third-zone contacts at slightly different times, so that, at the moment when the breaker 6 opened, on its third-zone timer-contact T3A, the corresponding timer-contact of the breaker 5 would either not yet have been made, or would have been made and broken as the timer-relay moved on past the setting of its contact-member T3A. In this manner, we do not need to have the quick-acting Z3A contact in the tripping circuit, but we may utilize a contact carried by an auxiliary relay CSA, which only needs to be fast enough to reopen before the timer-contact T3A makes contact again on its resetting stroke.

In the particular illustrated embodiment of our invention shown in Fig. 2, we have gone a step further than merely unequalizing the timer-settings at any particular station, and we have made the initiation of the timer-operation dependent upon current-direction as well as upon a third-zone distance-response. We have accomplished this result by utilizing the auxiliary relays CSA1, CSB1 and CSC1, the operating-coils of which are energized from the several circuits 29, such as the phase-A circuit which is in series with the directional contact DA as well as the auxiliary third-zone contact CSA. In this manner, in the illustrated case assumed in connection with Fig. 1, the timer T—A for the breaker 5 will not operate at all, being prevented from doing so by the DA contact, as long as any fault-current continued, and being prevented from operating by the dropping out of the distance-responsive element as soon as the fault was cleared by the opening of the breaker 6.

Other features of the illustrated form of embodiment of our invention, which have not been particularly discussed, are more or less conventional in the art, as shown in such patents as the Harder et al. Patent 2,144,493, and our Patent 2,255,934; and it is believed that such features will be readily understood without further detailed explanation.

While we have shown our invention in a single preferred form of embodiment, we wish it to be understood that such illustration is only illus-

trative, as the general features of our invention are susceptible of being incorporated in widely different structures and organizations. We desire, therefore, that the appended claims shall be accorded the broadest construction consistent with their language.

We claim as our invention:

1. A plurality of protective relaying equipments for respectively controlling a plurality of line-sectionalizing circuit-interrupting means in a plurality of line-sections terminating in a common bus at a relaying station, each equipment comprising first, second, and third-zone distance-responsive relaying-means for responding to line-faults at different distances from the relaying station, at least some of said relaying-means being selectively responsive when said faults are accompanied by a current-direction into the protected line-section at the relaying terminal, an auxiliary relay, means for utilizing a contact of the third-zone relay for performing a quick-response function, means for utilizing the same contact of the third-zone relay for controlling the energization of the auxiliary relay, a timing relay, means for utilizing the auxiliary relay in controlling the initiation of the timing-relay operation, means for utilizing the operations of said first and second-zone relays and said quick-response function in a plurality of control circuits for causing line-sectionalizing circuit-interrupter operations, and means for utilizing a timing-relay operation in causing a line-sectionalizing circuit-interrupter operation, the several relaying equipments at said station being so correlated that the aforesaid line-sectionalizing operations of different timing relays occur at different times.

2. A plurality of protective relaying equipments for respectively controlling a plurality of line-sectionalizing circuit-interrupting means in a plurality of line-sections terminating in a common bus at a relaying station, each equipment comprising first, second, and third-zone distance-responsive relaying-means for responding to line-faults at different distances from the relaying station, directionally responsive relaying-means for responding when said faults are accompanied by a current-direction into the protected line-section at the relaying terminal, an auxiliary relay, means for utilizing a contact of the third-zone relay for performing a quick-response function, means for utilizing the same contact of the third-zone relay for controlling the energization of the auxiliary relay, a timing relay, means for utilizing the auxiliary relay in controlling the initiation of the timing-relay operation, means for utilizing the operations of said directional relay and said first and second-zone relays and said quick-response function in a plurality of control circuits for causing line-sectionalizing circuit-interrupter operations, and means for utilizing a timing-relay operation in causing a line-sectionalizing circuit-interrupter operation, the several relaying equipments at said station being so correlated that the aforesaid line-sectionalizing operations of different timing relays occur at different times.

3. A plurality of protective relaying equipments for respectively controlling a plurality of line-sectionalizing circuit-interrupting means in a plurality of line-sections terminating in a common bus at a relaying station, each equipment comprising first, second, and third-zone distance-responsive relaying-means for responding to line-faults at different distances from the relaying

station, at least some of said relaying-means being selectively responsive when said faults are accompanied by a current-direction into the protected line-section at the relaying terminal, an auxiliary relay, means for utilizing a contact of the third-zone relay for performing a quick-response function, means for utilizing the same contact of the third-zone relay for controlling the energization of the auxiliary relay, a timing relay, means for utilizing the auxiliary relay in controlling the initiation of the timing-relay operation, means for utilizing the operations of said first and second-zone relays and said quick-response function in a plurality of control-circuits for causing line-sectionalizing circuit-interrupter operations, and circuit-interrupter control-circuit means, serially including contacts of said auxiliary relay, and said timing relay, for causing a line-sectionalizing circuit-interrupter operation, the several relaying equipments at said station being so correlated that the aforesaid line-sectionalizing contacts of different timing relays momentarily close at different times.

4. A plurality of protective relaying equipments for respectively controlling a plurality of line-sectionalizing circuit-interrupting means in a plurality of line-sections terminating in a common bus at a relaying station, each equipment comprising first, second, and third-zone distance-responsive relaying-means for responding to line-faults at different distances from the relaying station, directionally responsive relaying-means for responding when said faults are accompanied by a current-direction into the protected line-section at the relaying terminal, an auxiliary relay, means for utilizing a contact of the third-zone relay for performing a quick-response function, means for utilizing the same contact of the third-zone relay for controlling the energization of the auxiliary relay, a timing relay, means for utilizing the auxiliary relay in controlling the initiation of the timing-relay operation, means for utilizing the operations of said directional relay and said first and second-zone relays and said quick-response function in a plurality of control-circuits for causing line-sectionalizing circuit-interrupter operations, and circuit-interrupter control-circuit means, serially including contacts of said directional relay, said auxiliary relay, and said timing relay, for causing a line-sectionalizing circuit-interrupter operation, the several relaying equipments at said station being so correlated that the aforesaid line-sectionalizing contacts of different timing relays momentarily close at different times.

5. Protective relaying equipment for controlling a line-sectionalizing circuit-interrupting means at a terminal of a line-section to be protected, comprising first, second, and third-zone distance-responsive relaying-means for responding to line-faults at different distances from the relaying terminal, directionally responsive relaying-means for responding when said faults are accompanied by a current-direction into the protected line-section at the relaying terminal, an auxiliary relay, means for utilizing a contact of the third-zone relay for performing a quick-response function, means for utilizing the same contact of the third-zone relay for controlling the energization of the auxiliary relay, a timing relay, means for causing said timing relay to be energized in response to both said directional relay and said auxiliary relay, means for utilizing the operations of said directional relay and said first and second-zone relays and said quick-re-

sponse function in a plurality of control-circuits for causing line-sectionalizing circuit-interrupter operations, and circuit-interrupter control-circuit means, serially including contacts of said directional relay, said auxiliary relay, and said timing relay, for causing a line-sectionalizing circuit-interrupter operation.

6. Protective relaying equipment for controlling a line-sectionalizing circuit-interrupting means at a terminal of a line-section to be protected, comprising first, second, and third-zone distance-responsive relaying-means for responding to line-faults at different distances from the relaying terminal, at least some of said relaying-means directionally responding when said faults are accompanied by a current-direction into the protected line-section at the relaying terminal, an auxiliary relay, an oscillator-tube, means for utilizing a contact of the third-zone relay for quickly controlling the oscillator-tube with respect to its oscillation-generation, means for utilizing the same contact of the third-zone relay for controlling the energization of the auxiliary relay, means for utilizing the operations of said first and second-zone relays and said oscillator-tube in a plurality of control circuits for causing line-sectionalizing circuit-interrupter operations, and circuit-interrupter control-circuit means for utilizing contacts of said auxiliary relay for causing a line-sectionalizing circuit-interrupter operation.

7. Protective relaying equipment for controlling a line-sectionalizing circuit-interrupting means at a terminal of a line-section to be protected, comprising first, second, and third-zone distance-responsive relaying-means for responding to line-faults at different distances from the relaying terminal, directionally responsive relaying-means for responding when said faults are accompanied by a current-direction into the protected line-section at the relaying terminal, an auxiliary relay, an oscillator-tube, means for utilizing a contact of the third-zone relay for quickly controlling the oscillator-tube with respect to its oscillation-generation, means for utilizing the same contact of the third-zone relay for controlling the energization of the auxiliary relay, means for utilizing the operations of said directional relay, said first and second-zone relays, and said oscillator-tube, in a plurality of control circuits for causing line-sectionalizing circuit-interrupter operations, and circuit-interrupter control-circuit means for utilizing contacts of said directional relay and said auxiliary relay in series with each other for causing a line-sectionalizing circuit-interrupter operation.

8. Protective relaying equipment for controlling a line-sectionalizing circuit-interrupting means at a terminal of a line-section to be protected, comprising first, second, and third-zone distance-responsive relaying-means for responding to line-faults at different distances from the relaying terminal, at least some of said relaying-means directionally responding when said faults are accompanied by a current-direction into the protected line-section at the relaying terminal, an auxiliary relay, an electronic tube, means for utilizing a contact of the third-zone relay and the coil of the auxiliary relay in series with each other for together effecting a control over the condition of operation or nonoperation of the electronic tube, and means for utilizing the operations of said first and second-zone relays, said auxiliary relay and said electronic tube in the control of a plurality of control-circuits for caus-

ing line-sectionalizing circuit-interrupter operations.

9. Protective relaying equipment for controlling a line-sectionalizing circuit-interrupting means at a terminal of a line-section to be protected, comprising first, second, and third-zone distance-responsive relaying-means for responding to line faults at different distances from the relaying terminal, directionally responsive relaying-means for responding when said faults are accompanied by a current-direction into the protected line-section at the relaying terminal, an auxiliary relay, an electronic tube, means for utilizing a contact of the third-zone relay and the coil of the auxiliary relay in series with each other for together effecting a control over the condition of operation or non-operation of the electronic tube, and means for utilizing the operations of said directional relay, said first and second-zone relays, said auxiliary relay, and said electronic tube, in the control of a plurality of control-circuits for causing line-sectionalizing circuit-interrupter operations.

10. Protective relaying equipment for controlling a line-sectionalizing circuit-interrupting means at a terminal of a line-section to be protected, comprising first, second, and third-zone distance-responsive relaying-means for responding to line-faults at different distances from the relaying terminal, at least some of said relaying-means directionally responding when said faults are accompanied by a current-direction into the protected line-section at the relaying terminal, an auxiliary relay, an oscillator-tube, means for utilizing a contact of the third-zone relay and the coil of the auxiliary relay in series with each other for together quickly controlling the energization of the plate-cathode circuit of the oscillator-tube, means for causing the cathode of the oscillator-tube to be biased with respect to the potentials controlled by said third-zone contact, and means for utilizing the operations of said first and second-zone relays, said auxiliary relay and said oscillator tube in the control of a plurality of control-circuits for causing line-sectionalizing circuit-interrupter operations.

11. Protective relaying equipment for controlling a line-sectionalizing circuit-interrupting means at a terminal of a line-section to be protected, comprising first, second, and third-zone distance-responsive relaying-means for responding to line-faults at different distances from the relaying terminal, directionally responsive relaying-means for responding when said faults are accompanied by a current-direction into the protected line-section at the relaying terminal, an auxiliary relay, an oscillator-tube, means for utilizing a contact of the third-zone relay and the coil of the auxiliary relay in series with each other for together quickly controlling the energization of the plate-cathode circuit of the oscillator-tube, means for causing the cathode of the oscillator-tube to be biased with respect to the potentials controlled by said third-zone contact, and means for utilizing the operations of said directional relay, said first and second-zone relays, said auxiliary relay, and said oscillator-tube, in the control of a plurality of control-circuits for causing line-sectionalizing circuit-interrupter operations.

12. Protective relaying equipment for controlling a line-sectionalizing circuit-interrupting means at a terminal of a line-section to be protected, comprising first, second, and third-zone distance-responsive relaying-means for responding to line-faults at different distances from the

5 relaying terminal, at least one of said relaying-means directionally responding when said faults are accompanied by a current-direction into the protected line-section at the relaying terminal, an auxiliary relay, an electronic keyer including an oscillator-tube, a series dropping resistor for the oscillator-tube, a supply-circuit for the oscillator-tube, means for utilizing the series dropping resistor in a circuit between the anode of the oscillator-tube and the positive terminal of the supply-circuit, means for utilizing a contact of the third-zone relay and the coil of the auxiliary relay in series with each other in a circuit between the anode of the oscillator-tube and the negative terminal of the supply-circuit, means for causing the cathode of the oscillator-tube to be biased with respect to the terminals of said supply-circuit, and means for utilizing the operations of said first and second-zone relays, said auxiliary relay and said electronic keyer in the control of a plurality of control-circuits for causing line-sectionalizing circuit-interrupter operations.

13. Protective relaying equipment for controlling a line-sectionalizing circuit-interrupting means at a terminal of a line-section to be protected, comprising first, second, and third-zone distance-responsive relaying-means for responding to line-faults at different distances from the 25 relaying terminal, directionally responsive relaying-means for responding when said faults are accompanied by a current-direction into the protected line-section at the relaying terminal, an auxiliary relay, an electronic keyer including an oscillator-tube, a series dropping resistor for the oscillator-tube, a supply-circuit for the oscillator-tube, means for utilizing the series dropping resistor in a circuit between the anode of the oscillator-tube and the positive terminal of the supply-circuit, means for utilizing a contact of the third-zone relay and the coil of the auxiliary relay in series with each other in a circuit between the anode of the oscillator-tube and the negative terminal of the supply-circuit, means for causing the cathode of the oscillator-tube to be biased with respect to the terminals of said supply-circuit, and means for utilizing the operations of said directional relay, said first and second-zone relays, said auxiliary relay, and said electronic keyer, in the control of a plurality of control-circuits for causing line-sectionalizing circuit-interrupter operations.

14. Protective relaying equipment for controlling a line-sectionalizing circuit-interrupting means at a terminal of a line-section to be protected, comprising first, second, and third-zone distance-responsive relaying-means for responding to line-faults at different distances from the 30 relaying terminal, at least some of said relaying-means directionally responding when said faults are accompanied by a current-direction into the protected line-section at the relaying terminal, an auxiliary relay, carrier-current relaying-apparatus, an electronic keyer including an oscillator-tube, a series dropping resistor for the oscillator-tube, a supply-circuit for the oscillator-tube, means for utilizing the series dropping resistor in a circuit between the anode of the oscillator-tube and the positive terminal of the supply-circuit, means for utilizing a contact of the third-zone relay and the coil of the auxiliary relay in series with each other in a circuit between the anode of the oscillator-tube and the negative terminal of the supply-circuit, means for causing the cathode of the oscillator-tube to be biased with respect to the terminals of said supply-circuit, and means for utilizing the operations of said directional relay, said first and second-zone relays, said auxiliary relay, and said electronic keyer, in the control of a plurality of control-circuits for causing line-sectionalizing circuit-interrupter operations.

with respect to the terminals of said supply-circuit, means for utilizing the electronic keyer in the control of the carrier-current transmission of the carrier-current relaying-apparatus, and means for utilizing the operations of said first and second-zone relays, said auxiliary relay and said carrier-current relaying apparatus in the control of a plurality of control-circuits for causing line-sectionalizing circuit-interrupter operations.

15. Protective relaying equipment for controlling a line-sectionalizing circuit-interrupting means at a terminal of a line-section to be protected, comprising first, second, and third-zone distance-responsive relaying-means for responding to line-faults at different distances from the relaying terminal, directionally responsive relaying-means for responding when said faults are accompanied by a current-direction into the protected line-section at the relaying terminal, an auxiliary relay, carrier-current relaying-apparatus, an electronic keyer including an oscillator-tube, a series dropping resistor for the oscillator-tube, a supply-circuit for the oscillator-tube, means for utilizing the series dropping resistor in a circuit between the anode of the oscillator-tube and the positive terminal of the supply-circuit, means for utilizing a contact of the third-zone relay and the coil of the auxiliary relay in series with each other in a circuit between the anode of the oscillator-tube and the negative terminal of the supply-circuit, means for causing the cathode of the oscillator-tube to be biased with respect to the terminals of said supply-circuit, means for utilizing the electronic keyer in the control of the carrier-current transmission of the carrier-current relaying apparatus, and means for utilizing the operations of said directional relay, said first and second-zone relays, said auxiliary relay, and said carrier-current relaying apparatus, in the control of a plurality of control-circuits for causing line-sectionalizing circuit-interrupter operations.

16. Protective relaying equipment for controlling a line-sectionalizing circuit-interrupting means at a terminal of a line-section to be protected comprising first, second, and third-zone distance-responsive relaying-means for responding to line-faults at different distances from the relaying terminal, at least some of said relaying-means directionally responding when said faults are accompanied by a current-direction into the protected line-section at the relaying terminal, an oscillator-tube, a supply-circuit for the oscillator-tube, a control-circuit serially including a contact of the third-zone relay and a resistor, connected across said supply-circuit, a connection-means for connecting an intermediate point of said control-circuit to the plate of the oscillator-tube, means for causing the cathode of the oscillator-tube to be biased with respect to the terminals of said supply circuit, and means for utilizing the operations of said first and second-zone relays, and said oscillator-tube, in the control of a plurality of control-circuits for causing line-sectionalizing circuit-interrupter operations.

17. Protective relaying equipment for controlling a line-sectionalizing circuit-interrupting means at a terminal of a line-section to be protected comprising first, second, and third-zone distance-responsive relaying-means for responding to line-faults at different distances from the relaying terminal, directionally responsive relaying-means for responding when said faults are accompanied by a current-direction into the protected line-section at the relaying terminal, an oscillator-tube, a supply-circuit for the oscillator-tube, a control-circuit serially including a contact of the third-zone relay and a resistor, connected across said supply-circuit, a connection-means for connecting an intermediate point of said control-circuit to the plate of the oscillator-tube, means for causing the cathode of the oscillator-tube to be biased with respect to the terminals of said supply circuit, and means for utilizing the operations of said directional relay, said first and second-zone relays, and said oscillator-tube, in the control of a plurality of control-circuits for causing line-sectionalizing circuit-interrupter operations.

18. Protective relaying equipment for controlling a line-sectionalizing circuit-interrupting means at a terminal of a line-section to be protected comprising first, second, and third-zone distance-responsive relaying-means for responding to line-faults at different distances from the relaying terminal, directionally responsive relaying-means for responding when said faults are accompanied by a current-direction into the protected line-section at the relaying terminal, an auxiliary third-zone relay, an auxiliary directional relay, an oscillator-tube, a supply-circuit for the oscillator-tube, a control-circuit serially including a contact of the third-zone relay, the coil of the auxiliary third-zone relay, a contact of the auxiliary directional relay, and a resistor, connected across said supply-circuit, a connection-means for connecting an intermediate point of said control-circuit to the plate of the oscillator-tube, means for causing the cathode of the oscillator-tube to be biased with respect to the terminals of said supply circuit, and means for utilizing the operations of said directional relay, said first and second-zone relays, said auxiliary relay, and said oscillator-tube, in the control of a plurality of control-circuits for causing line-sectionalizing circuit-interrupter operations.
